TILT INDICATING APPARATUS

Maxwell F. Dorn, Jersey City, N. J., and Werner Rosenbaum, New York, N. Y., assignors to Bendix Aviation Corporation, Teterboro, N. J., a corporation of Delaware

Application October 27, 1954, Serial No. 465,084

10 Claims. (Cl. 33—205)

This invention relates to displaceable apparatus and particularly to the illumination of indicating apparatus. The invention applies especially, but not exclusively, to level indicators such as turn-and-bank indicators, inclinometers and the like for mobile craft.

It is an object of the present invention to provide improved displaceable apparatus.

It is another object of the invention to provide improved indicating apparatus which is economical in construction involving few parts and wherein an index body movable along a curved path is indirectly illuminated.

It is another object of the invention to provide means for indirectly illuminating an unattached index body displaceable along a curved path whereby a luminous simulated index of predetermined configuration, preferably in the general shape of a pointer, is produced with contrasting background by controlled reflection of the indirect light from selected portions of the index body.

It is another object of the invention to provide in a level indicator of the type having a spherical mass or ball displaceable along an arcuate path in an arcuate light-conducting tube filled with a light-conducting damping fluid, means for indirectly illuminating selected portions of the ball from selected portions of the tube so as to present to the observer a predetermined pattern of reflected light which remains substantially the same in size, shape and intensity when the ball occupies different positions along the arcuate path.

It is still another object of the invention to provide improved indicating apparatus including common light source means providing indirect illumination not only of an index body movable along an arcuate path but also of the indicia on an associated light-conducting member and/or of an accompanying light-conducting pointer.

The above and other objects and features of the present invention will become more apparent hereinafter from a consideration of the detailed description which follows taken together with the accompanying drawing wherein one embodiment of the invention is illustrated by way of example. In the drawing wherein like reference characters refer to like elements through the several views,

Fig. 1 is a front view of an inclinometer-type indicating device embodying the present invention with a portion of the cover assembly broken away to show the entire arcuate ball-carrying tube positioned in the lighting plate or dial adjacent to the indicia of one scale and to show an auxiliary pointer cooperating with a second scale;

Fig. 2 is a cross-sectional view of part of the device of Fig. 1 taken along the line 2—2;

Fig. 3 is a cross-sectional view of part of the device of Fig. 1 taken along the line 3—3 to show the mounting of one lamp and its position relative to the lighting plate;

Fig. 4 is a cross-sectional view of the lighting plate taken along the line 4—4 of Fig. 1 with other parts omitted;

Fig. 5 is a developed cross-sectional view of the lighting plate taken along the line 5—5 of Fig. 1 with other parts omitted;

2

Fig. 6a illustrates diagrammatically the index pattern of reflected light presented to the observer when the ball is simply illuminated directly by daylight or another ambient source of light;

5 Fig. 6b illustrates the broken index pattern presented to the observer when the ball is indirectly illuminated only by light rays transmitted from the two ends of the tube;

Fig. 6c illustrates the composite index pattern presented to the observer when the ball is indirectly illuminated 10 by light from the ends of the tube and also by light projecting from a narrow uncoated marginal portion of the tube;

Fig. 7a corresponds to Fig. 6c and illustrates the index pattern presented to observer when the arcuate tube is 15 positioned in the lighting plate as shown in Fig. 2;

Fig. 7b illustrates the index pattern presented to the observer if the arcuate tube is not positioned in the lighting plate as deeply as shown in Fig. 2; and

Fig. 7c illustrates the index pattern presented to the 20 observer when the arcuate tube is positioned in the lighting plate more deeply than shown in Fig. 2.

Turning to Figs. 1 and 2 there is illustrated an inclinometer-type level-indicating instrument suitable not only for direct illumination by daylight or other ambient light but also especially adapted for use in a darkened environment requiring so-called "night vision" and hence requiring indirect illumination accompanied by a minimum of stray light and glare. A flange portion 11 of housing 12 is secured to a flanged bezel portion 13 of a cover member 14 by screws 15. Sandwiched between the opposed flange portions is a sealing gasket 16. Within a recess in the cover member is a rubber gasket 17 surrounding the rim of a transparent window or cover glass 18. A beveled surface 19 of the cover member 35 serves as a frame for window 18.

A support structure is attached to the sides of the housing and includes an annular member 20. Secured to member 20 by screws 21 is a lighting plate or dial plate 22 of light-transmitting plastic material such as methyl 40 methacrylate, more commonly known as "Lucite" or "Plexiglas." As indicated in Fig. 1 the lighting plate is of generally semi-circular shape except for the flattened sides a—b and c—d. The lighting plate 22 is highly polished on all surfaces and has its front surface 23 and its peripheral surfaces 24 covered by a thin layer of white paint which in turn is covered by a layer of opaque paint or printer's ink, the dial indicia 25 and 26 of upper and lower scales on the front surface being cut out of the opaque layer to reveal the layer of white paint underneath. In an alternative construction, the indicia 25 and 26 may be cut or engraved in the front surface 23 of the lighting plate and the resulting recesses filled with white paint, the remaining flat surface portions of surface 23 being covered with a layer of opaque paint or printer's ink which may be applied by a roller. In either construction when light rays from one or more sources of light about to be described are transmitted by internal reflection through lighting plate 22, the indicia 25 and 26 are seen as white or colored light against a dark contrasting background provided by the opaque layer. If desired, selected portions of the back surface 27 of the lighting plate may be painted white to provide additional reflection and increase the intensity of illumination of the indicia.

60 65 The cover member 14 is provided with a pair of threaded apertures 28 which are aligned respectively with a pair of apertures 29 in the lighting plate 22. As indicated best in Fig. 3 a pair of conventional lamps 30 and 31 are threaded through the outer or front end of the cover member by means of a screw-driver inserted in a slot 32 provided in the end of each lamp. When each of the lamps is fully inserted, its filament 33 is preferably

70

located approximately midway between the outer and inner surfaces of the lighting plate and its contacts 34 and 35 make electrical contact with respective socket contacts 36 and 37 to complete a circuit between the filament and energizing means (not shown) within the housing 12.

The lighting plate 22 is provided with a conically shaped aperture 39 located midway between the lamps 30 and 31. The conical surface 40 preferably has a 45° slope with respect to the inner and outer surfaces of the lighting plate. Located behind aperture 40 is a mechanism 41 for angularly displacing a shaft 42 which in turn displaces a pointer 43. Pointer 43 may be composed of "Lucite" or "Plexiglas" which is highly polished on all surfaces and is tapered toward its tip end, the bottom or inner surface portion of the tip end preferably being coated with a layer of white paint 44. As shown in Fig. 2 the front edge surface portion 45 of the tail end of the pointer is flat and preferably has a 45° bevel or slope with respect to the front and back faces of the lighting plate. By this construction some of the light rays emitted from the lamps 29 and 30 are transmitted by internal reflection through the lighting plate and are then reflected from the 45° conical surface 40 outwardly from the lighting plate into the underside of pointer 43 regardless of the angular position which the pointer happens to be in. Such light rays are in turn reflected from the 45° tail-end surface 45 and transmitted by internal reflection to the pointed tip end portion of the pointer so that the tip end portion glows with uniform high intensity for the different angular positions of the pointer in contrast with the dark background provided by the dial portions which bear the white indicia 25 of the upper scale. Secured to the inner side of the cover member by screws 47 is an opaque shield member 48 of semi-circular shape to mask all but the tip of the pointer from the view of the observer.

An arcuate groove 49 is provided in the lighting plate. Groove 49 is defined by the flat surface 50 parallel to the front and back faces of the lighting plate, by the upper wall surface $e-f-g-h-i-j-k-l$ and by the lower wall surface $m_1-n_1-o_1-m_2-n_2-o_2$. Except as hereinafter noted, the three surfaces defining groove 49 are coated by a layer of white paint which in turn is covered by a layer of opaque paint. Positioned in groove 49 is an arcuate hollow tube 52 of light-conducting or transparent material such as "Pyrex" glass. In order to absorb shock or vibration a rubber strip 53 is interposed between the tube and surface 50 and a rubber strip 54 is interposed between the tube and surface $m_1-n_1-o_1-m_2-n_2-o_2$. The tube 52 is releasably secured in groove 49 by suitable means such as clamps 55 which have one end fastened to the lighting plate by means such as screws 55'.

A spherical solid ball 56 of highly polished tungsten carbide is confined inside tube 52 with a small clearance between the inner walls of the tube so that when the housing, lighting plate and tube are tilted to the left or right of dead center the ball correspondingly rolls along its arcuate path to the left or right of the zero position to an extent depending upon the direction and degree of tilt. Ball 56 cooperates with the indicia 26 of the lower scale to give an indication of the direction and degree of tilt. Tube 52 is preferably filled with a damping fluid such as carbon tetrachloride or water, although the fluid may be omitted if desired. The ends of tube 52 are sealed off by portions 57 and 58.

When lamps 30 and 31 are not energized and ball 56 is illuminated directly by daylight or other ambient light, the pattern of reflected light from the ball which the observer may see is indicated diagrammatically in Fig. 6a, the central portion serving as an index mark for the ball so that the position of the latter may be ascertained. Due to the presence of the tube and damping fluid the profile of the spherical ball appears generally elliptical in shape. Means will now be described for indirectly illuminating ball 56 from lamps 30 and 31 so as to obtain a

pattern of reflected light from the ball which simulates a pointer thereby giving an accurate reading and which remains substantially the same in size, shape and intensity when the ball occupies different positions along its arcuate path.

In Fig. 5 there is shown a developed section of lighting plate 22 taken along the arcuate line 5-5 of Fig. 1. As indicated in Fig. 5 the surface $e-f-g-h-i-j-k-l$ defining the upper boundary of arcuate groove 49 has portions $e-f-i-j$ and $g-h-k-l$ covered with an opaque layer, while portions $f-p-j-r$ and $q-g-s-k$ remain uncoated and serve in effect as windows 60 and 61, respectively, to permit some of the light rays transmitted through the lighting plate to escape from the plate and enter the adjoining end portions 63 and 64 of the arcuate tube 52. The end portions 63 and 64 are coated on the outside with a layer of white paint which extends around the circumference of the tube for approximately 270°, the remaining 90° which faces a respective one of the windows 60 and 61 being uncoated so as to receive the light rays from the lighting plate.

By this construction the light rays which enter the left-hand end of the tube from lamp 30 are transmitted by internal reflection through the damping fluid and along the tube until they strike the left-hand portion of ball 56. Similarly, the light rays which enter the right-hand end of the tube from lamp 31 are transmitted along the tube until they strike the right-hand portion of the ball. The resulting pattern of reflected light presented to the observer is indicated diagrammatically in Fig. 6b, the left-hand "strip" of light being derived from lamp 30 and the right-hand "strip" of light being derived from lamp 31. However, these strips are separated by a relatively wide dark area which makes accurate readings difficult, since the observer is required to estimate the geometrical center between the "strips" of light. In accordance with another feature of the invention means will now be described for closing or "filling-in" the gap at the outer ends of the "strips" so as to simulate an inverted U-shaped or V-shaped pointer which facilitates accurate readings by the observer.

Instead of covering the entire portion $p-q-r-s$ of the upper wall with opaque paint only portion $t-u-r-s$ is covered with opaque paint and a narrow marginal portion $p-q-t-u$ is left uncoated so as to permit some of the light rays transmitted through the lighting plate from lamps 30 and 31 to escape and enter an adjoining marginal portion of the arcuate tube 52. There is thus produced continuously along the tube a narrow reservoir of light of substantially uniform intensity which serves to "fill-in" the gap in the pattern of light reflected from the ball so that, as indicated diagrammatically in Fig. 6c, there results a composite pattern of light in the general form of an inverted U-shaped or V-shaped pointer presented against a contrasting dark background provided by the remaining non-reflecting portions of the ball, the size, shape and intensity of the pattern remaining substantially the same regardless of the position which the ball assumes along its arcuate path. If desired, the lighting plate or at least the portion which includes the upper wall $e-h-i-l$ may be replaced by a solid curved tube of light-conducting material such as "Lucite" supplied from one or both of the lamps and having a convex surface positioned adjacent to arcuate tube 52 and covered with opaque paint to provide an uncoated marginal strip and preferably also two end windows, which would be similar to what is provided on surface $e-h-i-l$ as shown in Fig. 5.

The pointer 43 and upper scale 25 may be used as a vernier to give a more sensitive indication of small angles of tilt so as to supplement the indication provided by ball 56 and lower scale 26, in which event the mechanism 41 for actuating pointer 43 may be adapted to sense independently the gravity forces or other condition

to which ball 56 responds. If desired, mechanism 41 may be adapted to sense a different condition than ball 56 and the upper scale 25 accordingly calibrated in units of such condition. Mechanism 41 may include a bellows arrangement or a gyroscope for example.

Various changes may be made in the shape, size or design of the parts and in the configuration or dimensions of the luminous pattern presented by the ball to the observer. For example, if groove 49 is cut less deeply into the lighting plate than illustrated in Fig. 2 so that tube 52 and ball 56 are located less deeply in the lighting plate, then the legs or sides of the inverted U-shaped or V-shaped pointer will appear shorter and will be spaced farther apart as represented diagrammatically in Fig. 7b. Similarly, if groove 49 is cut deeper so that tube 52 and ball 56 are positioned deeper in the lighting plate, then the legs or sides of the simulated pointer will appear longer and will be spaced closer together as indicated in Fig. 7c. Fig. 7a corresponds to Fig. 6c and represents diagrammatically the simulated pointer which may be obtained when tube 52 and ball 56 are inserted in the lighting plate to the extent indicated in Fig. 2. In certain applications it may prove desirable that the ball 56 of solid material be replaced by a displaceable body or mass of a different character, for example an air bubble formed within a suitable liquid in tube 52. Also, colored, light filters may be positioned between the lamp bulbs and tube 52 or the indicia. Furthermore, in certain applications it may be sufficient to provide a single indicium or reference mark at the zero mark of scales 25 or 26 rather than a series of graduations forming a scale. Also, indicia 25 and 26 could be provided on one or two separate light-conducting plates which are clamped into optical contact with an uncoated outer surface of lighting plate 22, or instead indicia 25 and 26 could be painted with radium paint or the like on separate opaque dials. Moreover, if simple incandescent lighting is not desired, luminescent material and other forms of radiant energy can be utilized in conjunction with a ball sensitive thereto to yield the simulated index pattern desired.

Although one specific embodiment of the invention has been illustrated and described in detail by way of example, it is to be expressly understood that the invention is not limited thereto. Various modifications may be made without departing from the spirit and scope of the appended claims as will now be apparent to those skilled in the art.

We claim:

1. In indicating apparatus, a hollow curved light conducting tube, a light-reflecting ball confined within said tube and displaceable along its curved interior in response to tilting of the tube, a light conducting member having a curved groove in which said tube is located, said member having an arcuate light emitting portion along a curved side of said tube, and means for directing light through said light emitting portion into said tube to illuminate said ball.

2. In indicating apparatus, a hollow arcuate tube of light-conducting material, a quantity of fluid disposed within said tube, a light-reflecting ball confined within said tube and adapted, upon tilting of the tube, to be displaced through the fluid along an arcuate path defined by the interior of said tube to an extent depending upon the degree of tilt of the tube, and means for producing a simulated pointer of light reflected from said ball, said means including means for projecting light rays into both ends of said tube for transmission by internal reflection along said tube and by refraction through said liquid to reflect from opposite surface portions of said ball facing the observer.

3. In indicating apparatus, a hollow curved light-conducting tube, a light-reflecting ball confined within said tube for displacement along a curved path therein

in response to tilting of the tube, and a light-conducting member having a curved groove in which said tube is located, said member having a light-emitting portion adjacent each end of said tube so that light rays pass from said portions into respective end portions of said tube for transmission inwardly along the tube toward said ball.

4. In indicating apparatus, a hollow arcuate light-conducting tube, a light-reflecting ball confined within said tube for displacement along an arcuate path therein in response to tilting of the tube, light source means, and a light-transmitting member having a reference indicium thereon adapted for illumination by light rays transmitted through said member from said source means and having an arcuate groove in which said tube is located, the convex wall of said member which defines part of said groove having a light-emitting portion adjacent each end of said tube so that other light rays transmitted through said member from said source means pass from said light-emitting portions into respective end portions of said tube for transmission inwardly along the tube toward said ball.

5. In indicating apparatus, a hollow arcuate light-conducting tube, a light-reflecting ball confined within said tube for displacement along an arcuate path therein in response to tilting of the tube, light source means, a light-transmitting member having indicia thereon adapted for illumination by a first group of light rays transmitted through said member from said source means and having an arcuate groove in which said tube is positioned, said tube being positioned in close proximity to the convex wall of said member which constitutes the convex boundary of said groove, and a layer of opaque material overlying said convex wall except for three selected portions of said wall, one of said selected portions being located adjacent to one end of said tube so that a second group of light rays transmitted through said member from said source means escape from said one portion and pass into said one end of the tube for transmission along the tube to reflect from a first surface portion of said ball, a second one of said selected portions being located adjacent to the other end of said tube so that a third group of light rays transmitted through said member from said source means escape

40 through said second portion and pass into said other end of the tube for transmission along the tube to reflect from a second surface portion of said ball, the third one of said selected portions comprising a relatively narrow marginal portion extending along the length 50 of the convex wall to interconnect said first and second portions so that a fourth group of light rays transmitted through said member from said source means escape through said marginal portion and pass into the immediate concave portion of said tube to reflect from a third 55 surface portion of said ball, whereby a substantially uniform composite pattern of light reflected from said ball is presented to the observer for different positions of said ball along said arcuate path.

6. Apparatus according to claim 5 wherein said pattern of reflected light has the configuration of an inverted U-shaped or V-shaped pointer.

7. Apparatus according to claim 5 wherein said light source means comprises a pair of lamps disposed in said light-transmitting member.

8. Apparatus according to claim 5 wherein a quantity of light-conducting fluid is confined within said tube for damping said ball.

9. Apparatus according to claim 5 wherein said indicia includes a first series of graduations with which said ball cooperates and a second series of graduations spaced from said first series, and wherein there is provided a light-conducting pointer member which cooperates with said second series of graduations and which is adapted to receive a fifth group of light rays trans-

mitted through said light-transmitting member from said light source means.

10. Apparatus according to claim 9 wherein said light-transmitting member has a conically shaped aperture which receives said fifth group of light rays and reflects said last-mentioned rays into a tail-end portion of said pointer member for transmission through said pointer member to the tip-end portion thereof.
